WATER ELIMINATOR FOR COOLING
TOWERS

Waldo R. Kell, Kansas City, Mo., assignor to The
Marley Company, Kansas City, Mo., a corpora-
tion of Missouri

Application September 15, 1937, Serial No. 164,003

3 Claims. (Cl. 183—75)

This invention relates to water eliminators for use at the top of cooling towers and has for its general object to produce an eliminator assembled in sections or units of a plurality of serpentine or zigzag passageways, so that the eliminators may be placed in or removed from operative position for repair or other purposes, without necessitating the services of a carpenter or other expert workman.

10 Another object of the invention is to produce a construction in which the louver slats or boards are in threaded relation to spacers and supports, and are more or less loosely held in position, since it has been found that this permits the 15 boards to accommodate themselves to warping with the result that there is less breaking, splitting or cracking of the boards and their lives are materially prolonged.

A further object of the invention is to produce 20 an eliminator which does not depend on the strength of driven or threaded metal parts for its life, since it has been found that wooden eliminators as at present constructed, have a life limited by the fastening means employed.

25 A still further object of the invention is to provide an eliminator of such nature that the turbulence of the air passing out through the eliminator is increased, thus inducing more complete deposition of moisture before the air exits 30 through the top of the labyrinth, this object being accomplished by a spacing of the boards or slats as will hereinafter appear.

35 With the general objects named in view, and others as will hereinafter appear, the invention consists in certain novel and useful features of construction and combinations of parts as herein- 40 after described and claimed; and in order that it may be fully understood, reference is to be had to the accompanying drawing, in which:—

45 Figure 1 is a top plan view of an eliminator embodying the invention.

Figure 2 is an enlarged cross-section through a portion of the eliminator as shown in Figure 1.

45 Figure 3 is an enlarged perspective view of one end of an eliminator slat-supporting grill member.

Figure 4 is a section through the upper end of a cooling tower taken longitudinally of the water eliminator bridging the tower.

50 In the drawing, where like reference characters identify corresponding parts in all of the figures, a plate-like member, which may be of any desired material, gauge or thickness, length and width, as will hereinafter more particularly appear, is formed to provide a plurality of serpentine or 55 zig-zag cross passageways of such width as to

more or less loosely receive in threaded relation louver boards or slats, as by providing pairs of spaced bars 1 and 2, or, of course, the passageways might be cut or punched out of sheet material. Each pair of spaced bars 1—2 is, by 5 preference, provided with stop or connecting portions 3 at their angles, for a purpose which will hereinafter appear.

In the drawing, the plate-like members, which for convenience may be referred to as grills, are 10 so formed that each pair of bars 1—2 are connected to adjacent pairs of bars by end pieces 4. In the construction shown the grills are of such length and width respectively, as to provide 15 eliminator units capable of receiving in threaded relation seven rows of slats or louver boards 5 arranged three deep or on three different levels, thus providing two breaks or changes in the direction of air currents passing up through the 20 eliminator. The proportions of parts is such that each slat is more or less loosely held to permit 25 it to warp or move slightly along its entire length, since it has been found that if such a slat is rigidly held at a plurality of points, it quickly splits and cracks in the endeavor to accommodate 30 itself to the unequal strains set up by the warping of the boards in service. Of course, the grill units may be made to provide a larger number of rows in either depth or in numbers counted horizontally, if desired. Each grill, if made as here shown, 35 is formed with male and female ends for interlocking engagement with adjacent grills.

The pairs of bars 1—2 are spaced apart such distances that air passing up between the slats 5 must change its direction of travel as previously 35 mentioned, thus causing the air to deposit its moisture on the inclined faces of the louver slats. In the preferred construction, the edges of adjacent louver boards or slats 5 are spaced apart by the stops 3, and although this construction has 40 been found non-essential, it is desirable as it increases the turbulence of air passing through the eliminator and thereby increases the deposition of moisture.

45 With a construction embodying the invention the louver slats 5 may be assembled in threaded loose relation with the desired number of grills, depending on the lengths of the slats which is determined by the span to be bridged or the width of the cooling tower. In the construction shown 50 in Figure 1, four grills are illustrated in supporting and spacing relation with each span or section of the eliminator. In practice, it has been found that by providing shelves or supporting surfaces 6 at the top of a cooling tower 7 and placing the 55

endmost grills adjacent to said shelves to stiffen the ends of the louver slats, each unit of the eliminator may be placed in position on the shelves without necessitating of employing securing or hold-down means of any kind as the weight of each section is distributed over the ends of all of the slats of the lowermost row. By making the grills of metal such as cast iron, it is found that the life of the eliminator is limited only by the life 10 of the slats or boards, which outlive other constructions where an effort is made to fasten the louver members rigidly in position.

From the above description, it will be apparent that I have produced a construction which embodies all of the features of advantage set forth as desirable; and while I have described and illustrated the preferred embodiment, it is to be understood that I reserve the right to all changes within the spirit of the invention and without the 20 ambit of the prior art.

I claim:—

1. A cooling tower having an open upper end and provided along two of its opposite sides with 25 supporting shoulders, said open end of the tower being closed by a water eliminator comprising a plurality of vertically spaced horizontal rows of slats spanning the tower from shoulder to shoulder with the lowermost row of slats resting on the 30 tower shoulders, and a series of plates having zig-zag arranged openings through which the slats are loosely threaded to provide tortuous passageways, the plates being spaced longitudinally along the

slats and out of direct contact with the cooling tower structure.

2. A cooling tower having an open upper end and provided along two of its opposite sides with supporting shoulders, said open end of the tower 5 being closed by a water eliminator comprising a plurality of vertically spaced horizontal rows of slats spanning the tower from shoulder to shoulder with the lowermost row of slats resting on the tower shoulders, and a series of plates having zig-zag 10 arranged openings through which the slats are loosely threaded to provide tortuous passageways, the plates holding the slats against contact with adjacent slats and being spaced longitudinally along the slats and out of direct contact 15 with the cooling tower structure.

3. A cooling tower having an open upper end and provided along two of its sides with supporting shoulders, said open end of the tower being closed by a water eliminator comprising series of 20 vertically spaced horizontal rows of slats, spanning the tower from shoulder to shoulder with the lowermost row of slats resting on the tower shoulders, and a series of plates having zig-zag 25 arranged openings through which said slats are loosely threaded, the plates being spaced longitudinally along the slats and out of direct contact with the walls of the cooling tower to hold a predetermined number of slats as a unit assembly, said plates being arranged in endwise abutting series, parallel to the supporting shoulders 30 of the cooling tower.
